ABSTRACT OF THE DISCLOSURE

Motor fuel composition comprising a mixture of hydrocarbons in the gasoline boiling range containing a detergent amount of a partial ester of a polyethoxylated N-hydrocarbyl-1,3-propanediamine having the formula:

in which R is an aliphatic hydrocarbon radical having from about 8 to 20 carbon atoms and R' is hydrogen or an acyl radical derived from a fatty acid having from about 8 to 20 carbons, at least one but not more than two of said R' substituents being an acyl radical.

BACKGROUND OF THE INVENTION

Modern internal combustion engine design is undergoing important changes to meet new federal standards concerning engine exhaust gas emissions. A major change in engine design recently adopted is the feeding of blowby gases from the crankcase zone of the engine into the intake air supply to the carburetor rather than venting these gases to the atmosphere as in the past. Further changes being considered involve the recycling of a part of the exhaust to the combustion zone of the engine in order to further reduce objectionable emissions. The recycled exhaust gases contain substantial amounts of deposit-forming substances which promote the formation of deposits in and around the throttle plate area of the carburetor. These deposits restrict the flow of air through the carburetor at idle and at low speeds so that an overrich fuel mixture results. This condition produces rough engine idling and stalling, and serves to increase the undesirable exhaust emissions which the engine design changes are intended to overcome.

Description of the prior art

U.S. 2,902,354 discloses an anti-stall gasoline composition containing N-alkyl-1,3-propanediamine additives for gasoline as well as alkylene oxide derivatives of these diamines exemplified by N-tetradecyl N,N',N'-tris-2-hydroxyethyl-1,1,3-propanediamine.

SUMMARY OF THE INVENTION

A class of partial esters of polyethoxylated N-hydrocarbyl-substituted 1,3-propanediamine compounds are provided as carburetor detergents when employed in a liquid hydrocarbon fuel for an internal combustion engine. These compounds, which are characterized by having a relatively long hydrocarbon radical attached to a nitrogen atom, as well as having one or two ester groups in the basic structure, appear to be unique in their detergency properties. Similar compounds in which all of the hydroxy groups have been esterified are essentially ineffective as carburetor detergents. Polyethoxylated N-hydrocarbyl-substituted 1,3-propanediamine compounds, which are precursors of the partial esters employed in the present invention, are susceptible to extraction by the tank water bottoms present in fuel distribution systems, making it difficult to maintain an effective concentration of the additive in the fuel composition.

The fuel composition of the invention prevents or mitigates the problem of deposits lay down in the carburetor of an internal combustion engine. When a gasoline of the invention is employed in a carburetor which already has a substantial build-up of deposits from prior operations, a rather severe test of the detergency property of a fuel composition, this gasoline is very effective for removing substantial amounts of the pre-formed deposits.

2

retor of an internal combustion engine. When a gasoline of the invention is employed in a carburetor which already has a substantial build-up of deposits from prior operations, a rather severe test of the detergency property of a fuel composition, this gasoline is very effective for removing substantial amounts of the pre-formed deposits.

DESCRIPTION OF THE PREFERRED EMBODIMENTS

10 The partial ester of a polyethoxylated N-hydrocarbyl-1,3-propanediamine of the invention is represented by the formula:

15 in which R is an aliphatic hydrocarbon radical having from 8 to 20 carbon atoms and R' is hydrogen or an acyl radical derived from a fatty acid having from about 8 to 20 carbon atoms, at least one but not more than two of said R' substituents being an acyl radical. A preferred embodiment of the invention is the monoester and diester in which least one but not more than two of said R' substituents represents an acyl radical having from about 16 to 18 carbon atoms and R is an aliphatic hydrocarbon radical having from 16 to 18 carbon atoms.

20 There is criticality in the structure of an ester of a polyethoxylated N-hydrocarbyl-1,3-propanediamine in order to provide an effective carburetor detergent. The full esters, that is, the triesters of polyethoxylated N-hydrocarbyl-1,3-propanediamine, are essentially ineffective as carburetor detergents when added to gasoline. In contrast to the triesters, the mono- and diesters of these compounds exhibit unusual effectiveness for removing carburetor deposits.

25 The mono- and diesters of the prescribed polyethoxylated N-hydrocarbyl-1,3-propanediamine are prepared by reacting 1 to 2 moles of a suitable fatty acid with approximately 1 mole of a polyethoxylated N-hydrocarbyl-1,3-propanediamine. This reaction is preferably conducted in an inert solvent. While the reaction temperature is not critical, it is preferred to conduct the esterification at a temperature ranging from about 160 to 210° C. with the particularly preferred temperature of reaction being from 170 to 200° C. The reaction is continued until the amount of the water of esterification collected indicates that the reaction has been completed or substantially complete. The following examples illustrate the preparation of partial esters employed in the fuel composition of the invention.

EXAMPLE I

30 63.6 grams (0.12 mole) of N-tallow-N,N',N'-tris-2-hydroxyethyl-1,3-propanediamine, 33.3 grams (0.12 mole) of a mixture of aliphatic fatty acids consisting principally of stearic acid and 2.0 grams of p-toluenesulfonic acid were combined in 300 milliliters of xylene. The mixture was azeotrope distilled to a temperature of 190 to 200° C. while under a nitrogen atmosphere. The reaction mixture was refluxed at this temperature for 6 hours during which time the water of esterification was collected. On completion of the reaction, the solvent was stripped from the reaction product. The monoesterified product, amounting to 95 grams, had a hydroxyl number of 125 as compared to the theoretical of 141.

EXAMPLE II

35 31.8 grams (0.06 mole) of N-tallow-N,N',N'-tris-2-hydroxyethyl-1,3-propanediamine, 33.3 grams (0.12 mole) of a fatty acid mixture consisting principally of stearic acid and 4.0 grams of p-toluenesulfonic acid were combined in 300 milliliters of xylene. The reaction mixture, maintained under a nitrogen atmosphere, was azeotrope distilled to a pot temperature of 190 to 200° C. The

reaction mixture was refluxed at this temperature for about 6 hours while the water of esterification was collected. On completion of the reaction, the solvent was stripped from the reaction product. The diesterified product, amounting to 62 grams, gave a hydroxyl number of 40 as compared to a calculated hydroxyl number of 53.

EXAMPLE III

42.4 grams (0.08 mole) of N-tallow-N,N',N'-tris-2-hydroxyethyl-1,3-propanediamine, 66.7 grams (0.24 mole) of a fatty acid mixture consisting principally of stearic acid and 4.0 grams of p-toluenesulfonic acid were combined in 300 milliliters of xylene. The reaction mixture, maintained under a nitrogen atmosphere, was azeotrope distilled to a pot temperature of 190 to 200° C. The reaction mixture was refluxed at this temperature for about 6 hours while the water of esterification was collected. On completion of the reaction the solvent was stripped from the reaction product. The triesterified product, amounting to 104 grams, gave a hydroxyl number of 19 as compared to a calculated hydroxyl number of 0.

EXAMPLE IV

48.3 grams (0.091 mole) of N-tallow-N,N',N'-tris-2-hydroxyethyl-1,3-propanediamine, 27.5 grams (0.096 mole) of a fatty acid mixture consisting principally of linoleic and oleic acids and 0.2 gram of p-toluenesulfonic acid were combined in 100 milliliters of xylene. The reaction mixture was azeotrope distilled to a pot temperature of 170° C. and allowed to reflux at this temperature for about 19 hours while the water of esterification was collected. On completion of the reaction, the solvent was stripped from the reaction product. The monoesterified product, amounting to 75 grams, had a hydroxyl number of 130 as compared to the theoretical of 125.

EXAMPLE V

532.0 grams (1.0 mole) of N-tallow-N,N',N'-tris-2-hydroxyethyl-1,3-propanediamine, 574 grams (2.0 moles) of a fatty acid mixture consisting principally of linoleic and oleic acids were combined in 350 milliliters of xylene. The reaction mixture was azeotrope distilled to a pot temperature of 180° C. and allowed to reflux at this temperature for about 3 hours. While the water of esterification was collected. After this time the reaction temperature was raised to 200° C. and the reaction mixture refluxed at this temperature for about 1 hour. The diesterified product, amounting to 1068 grams, was obtained as a 88 wt. percent solution in xylene. The xylene solution gave an OH No. of 71 as compared to the theoretical of 47.

When tested in gasoline at a concentration of 10.0 ptb. (pounds per thousand barrels of gasoline) for carburetor detergency in the second procedure designated II and described hereinbelow, this diester was essentially equivalent to the monoester of Example IV above.

Additional examples of partial esters which are effective as detergents in the gasoline compositions of the invention include the mono- and diesters of the following diamines:

N-octyl-N,N',N'-tris-2-hydroxyethyl-1,3-propanediamine;
N-monyl-N,N',N'-tris-2-hydroxyethyl-1,3-propanediamine;
N-undecyl-N,N',N'-tris-2-hydroxyethyl-1,3-propanediamine;
N-tridecyl-N,N',N'-tris-2-hydroxyethyl-1,3-propanediamine;
N-tetradecyl-N,N',N'-tris-2-hydroxyethyl-1,3-propanediamine;
N-pentadecyl-N,N',N'-tris-2-hydroxyethyl-1,3-propanediamine;
N-octadecenyl-N,N',N'-tris-2-hydroxyethyl-1,3-propanediamine.

Carboxylic acids used to prepare these esters are octanoic, nonanoic, decanoic, tetradecanoic, pentanoic, hexadecanoic and heptadecanoic.

The prescribed mono- and diesters of N-C₈₋₂₀ hydrocarbyl N,N',N'-hydroxyethyl-1,3-propanediamine are employed in the gasoline fuel composition in a concentration to provide effective carburetor detergent properties. In general, the esters are employed in a concentration ranging from about 0.0004 to 0.1 weight percent with a preferred concentration ranging from about 0.001 to 0.04 and a most preferred concentration ranging from 0.002 to 0.005 weight percent.

Any gasoline suitable for a spark-ignited, internal combustion engine can be used in the practice of this invention. In general, the base fuel will consist of a mixture of hydrocarbons in the gasoline boiling range, i.e., boiling from about 75° to 450° F. The hydrocarbon components can consist of paraffinic, naphthenic, aromatic and olefinic hydrocarbons. This gasoline can be obtained naturally or it can be produced by thermal or catalytic cracking and/or reforming of petroleum hydrocarbons. The base fuel will generally have a Research Octane Number above 85 and up to about 102 with the preferred range being from about 90 to 100.

The prescribed partial esters of N-hydrocarbyl-tris hydroxyethyl-1,3-propanediamine additive were tested for effectiveness in the carburetor detergency test. This test is run on Chevrolet V-8 engine mounted on a test stand using a modified four-barrel carburetor. The two secondary barrels of the carburetor are sealed and the feed to each of the primary barrels arranged so that the detergent additive fuel can run in one barrel and the reference fuel run in the other. The primary carburetor barrels were also modified to contain removable aluminum inserts in the throttle plate area so that the deposits formed on the inserts could be conveniently weighed.

Two procedures were used to determine the effectiveness of additive fuel for removing preformed deposits in the carburetor. In the first procedure, designated I, the engine is run for a period of time, usually 24 or 48 hours, using the base fuel as the feed to both barrels with engine blow-by circulated to the air inlet of the carburetor. The weight of the deposits on both sleeves is determined and recorded. The engine is then cycled for 24 additional hours with base fuel being fed to one barrel and the additive fuel to the other and no blow-by to the carburetor air inlet. The inserts are then removed from the carburetor and weighed to determine the difference between the performances of the additive and non-additive fuels for removing preformed deposits. After the aluminum inserts have been cleaned, they are replaced in the carburetor and the process repeated with the fuel feeds into the carburetor reversed in order to minimize differences in fuel distribution and carburetor construction. The results obtained in the two runs are averaged and the effectiveness of the base fuel and of the additive fuels for removing deposits expressed in percents.

In the second procedure, designated II, the engine is run for a period of time, usually 24 to 48 hours, using the base fuel as the feed to both barrels with engine blow-by circulated to the air inlet of the carburetor. The weight of the deposits on both sleeves is determined and recorded. The engine is then cycled for 24 additional hours with base fuel containing a recognized commercial additive at a concentration of 50 ptb. being fed to one barrel and the additive fuel to the other. During the cycle engine blow-by is circulated to the air inlet of the carburetor. The inserts are then removed from the carburetor and weighed to determine the difference between the performances of the additive and commercial detergent fuels for removing preformed deposits. After the aluminum inserts have been cleaned, they are replaced in the carburetor and the process repeated with the fuel feeds into the carburetor reversed in order to minimize differences in fuel distribution and carburetor construction. The re-

sults obtained in the two runs are averaged and the effectiveness of the reference fuel and of the additive fuels for removing deposits expressed in percents.

The base fuel employed in the following examples was a premium grade gasoline having an octane number of about 99.2 and containing 3 cc. of tetraethyl lead per gallon. This gasoline consisted of about 25.5 percent aromatic hydrocarbons, 95 percent olefinic hydrocarbons and 65 percent paraffinic hydrocarbons and boiled in the range from about 90° F. to 370° F.

Fuel compositions of the invention were tested in the Chevrolet Carburetor Detergent Test and the results set forth in Table I below. The percent effectiveness reported is the difference obtained by subtracting the percent effectiveness of the reference fuel from the percent effectiveness of the additive fuel.

TABLE I.—CARBURETOR DETERGENCY TEST

Run	Additive and conc. ¹	Test procedure	Percent effectiveness
1	Example I, 50	I	63
2	Example I, 10	I	66
3	do	I	57
4	Example II, 50	I	61
5	Example II, 10	I	47
6	Example III, 50	I	19
7	Example IV, 7.5	II	46

¹ Concentration in pounds per thousand barrels of gasoline.

The foregoing data, specifically Runs 1, 2, 3, 4, 5 and 7 illustrate the surprising effectiveness of the prescribed partial esters as carburetor detergent in motor fuel compositions. In contrast, Run 6, wherein the fully esterified tristearate ester of N-tallow-N,N',N' - tris - 2 - hydroxyethyl-1,3-propanediamine was employed in the gasoline composition, was essentially ineffective as a carburetor detergent.

The fuels of the invention may contain any additive conventionally employed in gasoline. Tetraalkyl lead, antiknock additives, dyes, corrosion inhibitors, anti-oxidants and the like can be beneficially employed without materially affecting the detergent additive of the invention. Gasolines containing from about 0.01 to 0.20 volume percent of a polymer, copolymer or the corresponding hydrogenated polymer or copolymer of a C₂ to C₆ unsaturated hydrocarbon having a molecular weight in the range of 500 to 3,500, preferably from 650 to 2600, as described in U.S. 3,502,451, which disclosure is incorporated in this application, in combination with the detergent of the present invention are particularly effective multifunctional fuels, compositions containing polypropylene and polyisobutylene of 80 to 1100 molecular weight at from about 0.025 to 0.1 volume percent being preferred.

I claim:

1. A motor fuel composition comprising a mixture of hydrocarbons in the gasoline boiling range containing from about 0.0004 to 0.1 weight percent of a partial ester of a polyethoxylated N-hydrocarbyl-1,3-propanediamine having the formula:

in which R is an aliphatic hydrocarbon radical having from about 8 to 20 carbon atoms and R' is hydrogen or an acyl radical derived from a fatty acid having from 8 to 20 carbon atoms, at least one but not more than two of said R' substituents being an acyl radical.

5 2. A motor fuel composition according to claim 1 in which the aliphatic hydrocarbons radicals represented by R and R' have from 14 to 20 carbon atoms.

10 3. A motor fuel composition according to claim 1 in which R consists predominantly of C₁₆ and C₁₈ aliphatic hydrocarbon radicals.

15 4. A motor fuel composition according to claim 1 in which said partial ester is essentially a mixture of mono- and diesters.

5 5. A motor fuel composition according to claim 1 in which said partial ester is a monostearate.

6. A motor fuel composition according to claim 1 in which said partial ester is a distearate.

7. A motor fuel composition according to claim 1 in which said partial ester is a monooleate.

8. A motor fuel composition according to claim 1 in which said partial ester is a dioleate.

9. A motor fuel composition according to claim 1 containing from about 0.001 to 0.04 weight percent of said 25 partial ester.

10. A motor fuel composition according to claim 1 in which said partial ester is a monolinoleate.

11. A motor fuel composition according to claim 1 in which said partial esters is a dilinoleate.

30 12. A motor fuel composition according to claim 1 containing from about 0.002 to 0.005 weight percent of said partial ester.

13. A motor fuel composition of claim 1 which additionally contain from about 0.01 to 0.20 volume percent 35 of (1) a polymer of a C₂ to C₆ unsaturated hydrocarbon (2) a copolymer of a C₂ to C₆ unsaturated hydrocarbon, or (3) the corresponding hydrogenated polymer or copolymer, said polymer or copolymer having a molecular weight in the range from about 500 to 3,500.

40 14. A motor fuel composition according to claim 1 containing from about 0.025 to 0.1 volume percent of polypropylene having a molecular weight ranging from about 800 to 1100.

45 15. A motor fuel composition according to claim 1 containing from about 0.025 to 0.1 volume percent of polyisobutylene having a molecular weight ranging from about 800 to 1100.
